E. H. TAYLOR,
SAFETY DEVICE FOR CORNER STAYING MACHINES,
APPLICATION FILED MAR. 23, 1914.

1,111,329.

Patented Sept. 22, 1914.

UNITED STATES PATENT OFFICE.

EUGENE H. TAYLOR, OF HYDE PARK, MASSACHUSETTS.

SAFETY DEVICE FOR CORNER-STAYING MACHINES.

1,111,329.

Specification of Letters Patent. Patented Sept. 22, 1914.

Application filed March 23, 1914. Serial No. 826,523.

To all whom it may concern:

Be it known that I, EUGENE H. TAYLOR, a citizen of the United States, residing at Hyde Park, county of Norfolk, State of Massachusetts, have invented a certain new and useful Improvement in Safety Devices for Corner-Staying Machines, of which the following is a specification, reference being had therein to the accompanying drawings.

10 My invention has for its object to provide a safety device by means of which the upper die of a corner staying machine shall be prevented from coming down onto the lower die or interposed box if the fingers of the operator are between the dies. Heretofore injury to the hands and fingers of operators has frequently resulted from the use of corner staying machines of the ordinary well known type. The mechanism embodying 15 my invention is simple and efficient and does not interfere with the normal operation of the machine.

The invention will be fully understood by reference to the following specification, 20 taken in connection with the accompanying drawings, and the novel features thereof are pointed out and clearly defined in the claims at the close of this specification.

In the drawings, Figure 1 is a side elevation of a corner staying machine to which is applied the safety device embodying my invention. Fig. 2 is a front view of the upper portion of the machine and parts shown in Fig. 1. Fig. 3 is a front view showing the 35 parts in the position occupied by them after the safety device has operated.

Referring to the drawings at A is shown the form of lower die member and at B the upper die member. At C is shown the main shaft and at D a crank pin by means of which the upper die member is reciprocated vertically. The stay strip is shown at E. These parts are well known and commonly employed in corner staying machines.

45 The main shaft C supports a cam 40, which actuates a cam follower 41 forming part of a lever 42 pivoted at 43 to the frame of the machine. At 44 is shown another lever parallel to the said lever 42 and pivoted also to the frame of the machine as shown at 45. The levers are connected and will now be described and, therefore, are swung to and fro by the cam 40 once for each revolution of the machine. The cam 50 follower 41 is held against the cam by a spring 46 attached to the lever 42. Secured

to the lower ends of said levers 42 and 44 by means of pins 11, 11, is a bar 12, the front end 80 of which is bent at right angles to the main portion of the bar so that it extends 60 sidewise into the space between the upper and lower die members. The front end 80 is preferably bent to the form shown in Fig. 2 to conform to the space between the two dies formed by the reentrant angle of the 65 upper die. It forms what for convenience may be called the hand-contact member and it will be seen that it reciprocates back and forth into and out of the space between said upper and lower die members, being forward in the position shown in Fig. 1 at the time when the dies come together and being back between the upper and lower die members when the die members are separated. The two levers 42 and 44 also carry a bunter 13 on swinging pins 14, 14. The front end of the bunter 13 contacts at the forward end of the stroke with a movable stop 15 pivoted at 16 to the frame of the machine and held normally in vertical position by 70 means of the spring 23. Said stop is carried by the frame of the machine and therefore does not move vertically.

The connecting rod by means of which the upper die member B is actuated from 85 the crank pin D is formed in two parts 17 and 18 hinged together at 19. A spring 26 secured to two lugs 21 and 22 on the parts 17 and 18 tends to hold the two members 17 and 18 in the position shown in Fig. 2, to 90 form normally a straight connecting rod. It will be seen that the parts 17 and 18 of the connecting rod are relatively wide and that the center of the pintle 19 of the hinge is considerably to one side of the median line 95 of the connecting rod, the ends of the two members being in contact with each other, so that heavy pressure may be exerted upon the stay strip without putting undue strain on the hinge members or pintle. The connecting rod member 17 is pivoted at 24 to the cross head 25 on which the die member B is secured. A lever 26 projects from one side of the connecting rod member 17 and its end 81 is located directly above the upper end of the movable stop 15, when said movable stop is in vertical position. The connecting rod member 17 and the lever 26 secured thereto together form a bell crank 100 lever.

In the normal operation of the machine, the bunter 13 knocks the movable stop 15

out of the path of the arm 26 which is integral with the lever member of the connecting rod so that the connecting rod is free to move the die B down into contact with the stay strip located over the box on the lower die member. If the fingers of the operator are between the upper and lower die members, the hand-contact piece 12 cannot be pushed forward by the levers 42 and 44 and the bunter 13 will not move the movable stop 15 out of the path of the arm 26. The movable stop 15 will thus remain in vertical position and the arm 26 will contact with the upper end of the movable stop 15. This will prevent in part the farther downward movement of the cross head 25 and upper die member B, bending the two parts of the connecting rod about the hinge 19 and extending the spring 20. It will therefore be seen that the two die members cannot come together if the hand-contact lever is prevented from moving forward out of the space between the upper and lower die members. The continued rotation of the eccentric permits the spring 20 to straighten the connecting rod again so that the machine will operate normally on the next stroke if the hand-contact lever is not displaced.

From the foregoing it will be seen that the presence of the operator's hand between the dies will prevent the dies coming together, and therefore the machine may be run with complete safety even by a careless operator. It will also be seen that the hand-contact member tends to push the hand of the operator out of the space between the die members, and if the spring 46 is made stiff enough will always do so; I prefer however not to rely on this action because if the machine is run at high speed the hand-contact member will itself injure the operator.

What I claim is:

1. The combination with a corner staying machine having upper and lower die members, a connecting rod operating one of said die members of a hand-contact member moving into and out of the space between

the die members and means acting on said connecting rod and operated by the said hand-contact member to prevent the dies coming together when the said member is between the dies.

2. The combination with a corner staying machine having upper and lower die members of a connecting rod operating one of said die members, said connecting rod being formed in two parts hinged together, a hand-contact member moving into and out of the space between the die members and connections between said hand-contact member and the connecting rod whereby the said members are caused to swing about said hinge if the hand-contact member is prevented from moving out of the space between the said two die members.

3. In a corner staying machine, the combination with upper and lower die members one of which is formed to have a reentrant angle, of a hand-contact member forming part of a safety device, a part of said hand-contact member being at times between said dies and being shaped to correspond to the space formed between the dies.

4. In a corner staying machine, the combination with upper and lower die members, of a connecting rod operating one of said die members, said connecting rod being made in two parts hinged together, a hand-contact member moving into and out of the space between the two members, an arm secured to one of the parts of the connecting rod and operating to bend the members of the connecting rod about the hinge connection, a vertical stop normally in the path of movement of the said arm, and connections between the said stop and the hand-out of the path of the arm when the hand-out of the path of the arm when the hand-contact member is out of the space between the two dies.

In testimony whereof I affix my signature, in presence of two witnesses.

EUGENE H. TAYLOR.

Witnesses:

GEORGE P. DIKE,
ALICE H. MORRISON.
